UNITED STATES PATENT OFFICE.

HOWARD H. JOHNSTON, OF EDGEWOOD, PENNSYLVANIA, ASSIGNOR TO WESTINGHOUSE ELECTRIC & MANUFACTURING COMPANY, A CORPORATION OF PENNSYLVANIA.

ELECTRIC LOCOMOTIVE.

Application filed January 6, 1921. Serial No. 435,319.

To all whom it may concern:

Be it known that I, HOWARD H. JOHNSTON, a citizen of the United States, and a resident of Edgewood, in the county of Allegheny and State of Pennsylvania, have invented a new and useful Improvement in Electric Locomotives, of which the following is a specification.

My invention relates to electric locomotives and particularly to means for mounting control apparatus therein.

One object of my invention is to provide a construction wherein the main control switching units are so mounted within a housing as to be conveniently accessible for renewals or repairs.

Another object of my invention is to arrange certain of the switching apparatus in such manner that they may be swung clear of the enclosing compartment and may be removed therefrom, either as units or collectively, and, when swung to exposed position, will uncover other portions of the apparatus which may be secured to the stationary portions of the compartment.

My invention provides for the securing of certain of the main controlling and switching units to the inner side of the hinged cover plates which may be swung outwardly, carrying with them the apparatus secured thereto, and, if desired, these hinged cover plates may be removed and other cover plates and switching apparatus substituted therefor.

As shown in the accompanying drawings: Figure 1 is an end elevational view of a mine locomotive, a portion being broken away to show the application of my invention thereto, and

Fig. 2 is a view, in side elevation, showing the cover plates in raised positions.

My invention is shown as applied to an ordinary mine locomotive 3, provided with a usual trolley 4 and a compartment 5 for housing the control apparatus.

The control apparatus may be of any desired character, such as contactors 6 and a reversing switch 7. These parts function in the usual manner and will not be described herein in detail.

The contactors 6 are individually secured to a pair of iron bars 8, through the medium of blocks 9, preferably of wood or other insulating material, and the bars 8 are, in turn, secured to a hinged cover plate 10 by

means of bolts 11. The bars 8 are insulated from the cover plate 10 by members 12 of any suitable insulating material.

The reversing switch 7 is secured to a hinged cover plate 13 and is provided with a cover 14. When the hinged cover plate 13 is swung to exposed position, the plate 14 may be removed from the reversing switch if only minor repairs are to be made. For more extensive repairs or for the substitution of a new switch, a flexible conductor 15 may be disconnected therefrom and the switch removed from the plate 13, or the plate 13 may be removed and be replaced by another plate and switch.

The contactors 6 may be removed independently by disconnecting terminals 16 and unfastening the contactors from the blocks 9 or they may be removed collectively by breaking the electrical connection, as at 17, and removing the cover plate 10 from its hinges, or by disconnecting the bars 8 from the cover plate.

The advantage of the foregoing arrangement resides in the fact that repairs or replacements may be quickly made and, if a portion only of the apparatus requires repair, that particular unit may be quickly removed and another unit substituted therefor.

Besides insuring easy accessibility of the parts carried by the hinged covers of the compartment, these parts, when swung to open position, expose other apparatus in the compartment, such as resistance grids, and serve to render such other parts also easily accessible for replacement or repairs.

While my invention is shown as applied to a mine locomotive, it obviously may be applied to various other types of apparatus wherein it is desired to render mechanism that is located within a housing easily accessible for replacement or repair.

I claim as my invention:

1. In an electric locomotive, a compartment for housing the controlling apparatus, a removable closure member for the compartment, supporting means for the controlling apparatus comprising a panel of non-conducting material, a supporting bar for the panel, and an insulated connection between the supporting bar and the cover plate.

2. In an electric locomotive, a housing compartment provided with a removable

cover member, controlling units carried by the cover member, a unit-supporting member detachably secured to the cover member, and means for detachably securing the 5 controlling units individually to the supporting member.

3. In an electric locomotive, a compartment provided with a removable cover member to which is secured contactor units 10 mounted for removal either independently or collectively, and a second hinged cover member to which the reversing switch is secured.

4. In an electric locomotive, the combination 15 with a housing compartment provided with a removable cover member, of supporting means comprising a bar secured to the cover member by insulated attaching means and provided with means for supporting the 20 electric controlling apparatus.

5. In an electric locomotive, a compartment for housing the control apparatus comprising a plurality of hinged walls and cover members, said control apparatus being 25 removably mounted on said hinged members.

6. In an electric locomotive, a compartment for housing the control apparatus comprising a plurality of hinged walls and cover members, some of said hinged members constituting panels for mounting the 30 control apparatus.

7. In an electric locomotive, a compartment for housing the control apparatus comprising a plurality of hinged walls and 35 cover members, some of said hinged members constituting panels for mounting the control apparatus, said panels being removable as a unit.

8. In an electric locomotive, a compartment for housing the control apparatus comprising a plurality of insulating panel members movably mounted on a frame, having the control apparatus mounted thereon, 40 said panels constituting an operating unit 45 which may be replaced as to its several co-operating parts.

In testimony whereof, I have hereunto subscribed my name this 27th day of December 1920.

HOWARD H. JOHNSTON.
